UNITED STATES PATENT OFFICE

WILLIAM A. GIBSON, OF ALLENTOWN, PENNSYLVANIA, ASSIGNOR TO BRADLEY PULVERIZER COMPANY, OF ALLENTOWN, PENNSYLVANIA, A CORPORATION OF MASSACHUSETTS

ADJUSTABLE SCREEN DIAPHRAGM FOR TUBE MILLS, ETC.

Application filed October 13, 1930. Serial No. 488,831.

This invention relates to improvements in tube mills of the compartment type which comprises a rotatable drum having at one end an inlet for the material to be ground, and at the other end an outlet for the ground material, the drum being divided into a series of compartments by screen diaphragms. The several compartments of such mills are provided with grinding members, such as pebbles, balls, rods, etc., to facilitate the grinding operation, the grinding members in the first or initial grinding compartment at the inlet end of the drum being relatively large, with successively smaller grinding members in the respective succeeding compartments.

In order to provide a maximum efficiency of grinding operation for different materials, the relative lengths of the successive grinding compartments desirably is varied in accordance with the character of the material to be ground. This requires an adjustment of the position of the diaphragms which separate one compartment from the next.

In tube mills of this type the drum is provided with a lining of wear-resistant material, and in usual constructions the diaphragms, which separate the several compartments from one another, extend to the interior surface of the drum proper, so that the ends of the lining of each compartment abut against the faces of the respective diaphragms. In order, therefore, to adjust the position of the diaphragms it is necessary to remove the lining and to vary the length of the lining for the several compartments in accordance with the desired length of such compartments. This requires the removal of the greater part of the lining of the mill.

The principal object of the present invention is to provide a tube mill construction in which the diaphragms may be readily adjusted to provide successive compartments of desirable relative lengths.

A further object of the invention is to provide a drum with a lining presenting an interior surface of such character as to permit the adjustment of the diaphragms, and which will prevent rotation of the diaphragms relatively to the drum.

These and other objects and features of the invention will more fully appear from the following description and the accompanying drawings and will be particularly pointed out in the claims.

In the drawings:

Fig. 1 is a vertical longitudinal sectional view of a tube mill embodying the invention;

Fig. 2 is a transverse detail sectional view on line 2—2 Fig. 1, viewed from the left toward the right; and,

Fig. 3 is a fragmentary view illustrating the diaphragm adjustably mounted upon a hollow shaft.

The grinding mill, which is illustrated in the accompanying drawings, comprises a cylindrical drum 1, having at its ends heads 2 and 3 provided respectively with preferably integral hollow trunnions 4 and 5 which are mounted in suitable, preferably hollow, bearings 6 and 7. The ends of the drum are secured to the heads by angle plates 8 and 9 which are welded, riveted, bolted, or otherwise secured to the drum and to the head. A driving gear 10, which is secured to the angle plate 9, is actuated by a pinion (not shown) driven in any suitable manner as is usual in such constructions.

The hollow trunnion 4 provides an inlet through which the material to be ground is introduced into the drum, and the hollow trunnion 5 provides an outlet through which the ground material is delivered from the drum.

Any suitable means may be provided for introducing the material into the inlet trunnion of the drum. In the construction illustrated a scoop 11, which is connected to the end of the hollow inlet trunnion 4, and has a mouth 12 adapted to pass through a feed box 13, provides means for feeding the material into the drum.

The ground material is delivered from the outlet trunnion 5 into a suitable receptacle 14 from which it is conveyed to a suitable classifier in accordance with usual practice.

In usual mills of the compartment type the diaphragms, which divide the drum into the several compartments, comprise circular

screen plates, or pairs of narrowly separated screen plates, the peripheries of which contact with the inner face of the cylindrical wall of the drum, and the linings of the several compartments abut at their ends against the opposite faces of the diaphragms. The diaphragms, therefore, are in fixed position and cannot be adjusted without removal and replacement of the greater portion of the lining. The present invention provides means for permitting adjustments of the diaphragms longitudinally of the drum to vary the relative length of the compartments without the necessity of removing and replacing any portion of the lining. This is accomplished by providing a rigid member extending longitudinally of and co-axially with respect to the drum and rigidly secured thereto by suitable spiders, or other supports, and slidably mounting the diaphragm upon said rigid member.

In the construction illustrated in the drawings this is accomplished by providing a central shaft 15 which may be a solid shaft, as illustrated in Fig. 2, or a hollow shaft 15 α , as illustrated in Fig. 3. The shaft extends axially of the drum and is secured to the drum by spiders 16 and 17 which in turn are rigidly secured respectively within the hollow inlet and outlet trunnions 4 and 5.

Other spiders may be employed within the drum if desired, or if necessary by reason of the length of the drum to support the shaft rigidly therein.

The diaphragms are slidably mounted upon the shaft 15 and desirably are provided with hubs with suitable means for securing the hubs of the diaphragm to the shaft in any desired adjusted position.

In order further to secure the diaphragms against rotation relatively to the drum, the drum is provided with a lining having ribs extending longitudinally of the drum in parallelism with the axis thereof, and the peripheries of the diaphragms are provided with recesses complementary to the ribs acting, when in engagement with the ribs, positively to prevent any relative rotative movement between the diaphragm and the drum.

In the preferred construction illustrated the lining comprises a series of longitudinally extending cylindrical sector-shaped plates 18, of wear-resistant material, fitting within the drum to provide a continuous lining therefor.

Preferably each of the lining plates 18 is provided with a central rib 19 having inwardly inclined edges 20 and a flat central face 21.

The screen diaphragm may consist of a flat circular plate 22 having a periphery complementary to the ribbed surface of the lining and with the central hub 23, which is adjustably mounted upon the shaft 15 or 15 α , or the diaphragm may comprise a plurality of parallel, narrowly spaced, screen plates 24 connected together with suitable

separators therebetween and having respectively peripheries complementary to the ribbed inner surface of the lining of the drum.

Desirably the circular diaphragms may be constructed in sections as quadrants 25 having circular peripheries 26 and secured by welding, or otherwise, to central hubs 27 slidably fitted upon the shaft 15. The hubs of the diaphragms may be secured to the shaft in any suitable manner as by a key 28, mounted in suitable key-ways extending longitudinally of the shaft and the hub, or by set screws 29, or other suitable fastening means.

For convenience in construction, sector-shaped plates 30, provided with recesses 31 complementary to the ribs 19, may be secured to the peripheral face or faces of the diaphragms by rivets 32, the rivets 32 extending also through suitable spacers if the diaphragms are provided with a plurality of narrowly separated screen plates.

The peripheral plates 30, by overlapping the abutting edges of the sections of the diaphragm plates to which they are secured, serve to strengthen the diaphragm construction.

If desired the single diaphragm construction 22, illustrated in Fig. 1, may have a circular periphery with plates having recesses complementary to the ribs 31 of the lining secured to one or both faces of the plates as illustrated in Fig. 2.

By reason of such constructions the screen diaphragms may be adjusted to provide compartments of any desirable relative length, thereby providing the proper length of the respective compartments to cause the material travelling through the drum to be retained in the compartment until it is subjected to the desired pulverizing action of the particular balls, or other grinding members of such compartment.

By reason of the present invention, therefore, the adjustment of the diaphragms may be easily and quickly made to enable the mill to operate at a maximum efficiency upon any particular kind of material.

Furthermore, by reason of the present invention the relative length of the compartments may be quickly adjusted without the necessity of removal or replacement of any portion of the lining, thereby saving a very considerable cost in labor and materials which otherwise would be required to permit such adjustment in mills of usual types.

Having thus described the invention, what is claimed as new, and desired to be secured by Letters Patent, is:

1. A tube mill comprising a rotatable drum having at one end an inlet for the material to be ground and at the other end an outlet for the ground material, a rigid member secured to said drum and extending axially thereof, a screen diaphragm dividing the drum into

a plurality of grinding compartments, means for adjustably securing said diaphragm to said rigid member in different positions longitudinally of the drum, whereby the relative 5 lengths of adjacent grinding compartments may be varied, and complementary means upon the periphery of the diaphragm and the inner face of the drum for preventing relative rotative movement between said diaphragm and said drum.

2. A tube mill comprising a rotatable drum having at one end an inlet for the material to be ground and at the other end an outlet for the ground material, a rigid member extending axially thereof, a transverse screen diaphragm having a hub slidably mounted upon said rigid member, means for securing said hub to said rigid member in adjusted positions longitudinally of the drum to vary 15 the relative lengths of adjacent compartments, and complementary interengaging members upon the periphery of the diaphragm and upon the inner surface of the drum operable to permit adjustment of the 20 diaphragm longitudinally of the drum, but to prevent relative rotation therebetween.

3. A tube mill comprising a rotatable drum having at one end an inlet for the material to be ground and at the other end an outlet 30 for the ground material, a shaft rigidly secured to said drum and extending axially thereof, a wear-resistant lining for said drum having a plurality of longitudinally extending ribs, a transverse circular screen diaphragm formed of sections lying in the same 35 plane and having a hub slidably mounted upon said shaft, a circular series of peripheral plates secured to said drum overlapping the abutting edges of said sections and secured 40 to said sections, and presenting edges complementary to and slidably fitting the ribbed surface of said lining, and means for securing said hub to said shaft.

4. A tube mill comprising a rotatable drum 45 having at one end an inlet for the material to be ground and at the other end an outlet for the ground material, a rigid member secured to said drum extending axially thereof, a wear-resistant lining for said drum having a plurality of ribs extending longitudinally of said drum in parallelism with the axis thereof, a transverse circular screen diaphragm having a hub slidably mounted upon 50 said rigid member and provided with a circular series of peripheral plates presenting edges complementary to and slidably fitting the ribbed surface of said lining, and means for securing said hub to said rigid member.

5. A tube mill comprising a rotatable drum 60 having at its ends hollow trunnions providing respectively an inlet for the material to be ground and an outlet for the ground material, a shaft extending axially of said drum mounted at its ends in spiders fixedly secured within said hollow trunnions, a lining for 65

said drum comprising a circular series of wear-resistant plates having ribs extending longitudinally of the drum in parallelism with the axis thereof, a plurality of screen diaphragms having peripheral members complementary to and slidably fitting the ribbed surface of said lining and having hubs slidably mounted upon said shaft to permit adjustment of the diaphragms longitudinally of the drum and thereby vary the relative lengths of said compartments, and means for securing said hubs to said shaft.

In testimony whereof, I have signed my name to this specification.

WILLIAM A. GIBSON.
